TOOL FOR REPAIRING CLOCKS

Charles O. Terwilliger, Jr., 11 Masterton Road,
Bronxville, N.Y.

Filed Mar. 30, 1962, Ser. No. 69,513

Term of patent 14 years

(Cl. D54—13)

FIGURE 1 is a side view of the tool for repairing clocks showing my new design;

FIGURE 2 is a top view of the tool;

FIGURE 3 is a right end view of the tool as shown in FIGURE 1; and

FIGURE 4 is a left end view of the tool as shown in FIGURE 1.

I claim:

The ornamental design for a tool for repairing clocks, substantially as shown.
